UNITED STATES PATENT OFFICE

132,253

DESIGN FOR A PENNANT OR SIMILAR ARTICLE

Harry R. Ferguson, Battle Creek, Mich.

Application February 19, 1942, Serial No. 105,915

Term of patent 7 years

To all whom it may concern:

Be it known that I, Harry R. Ferguson, a subject of the King of England, residing at Battle Creek, in the county of Calhoun and State of Michigan, have invented a new, original, and ornamental Design for a Pennant or Similar Article, of which the following is a specification, reference being had to the accompanying drawing, forming part thereof.

The figure is a plan view of a pennant or similar article, showing my new design.

I claim:

The ornamental design for a pennant or similar article, as shown.

HARRY R. FERGUSON.
